CLAIM

The ornamental design for a television remote control with phone controlling buttons, as shown and described.

DESCRIPTION

FIG. 1 is a front view for a television remote control with phone controlling buttons showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a rear perspective view thereof.

The circles on the rear of the remote control show holes. The areas inside the circles are not part of the claimed design. The broken lines in the figures represent portions of the television remote control with phone controlling buttons that form no part of the claimed design.
